Patented May 22, 1917.

UNITED STATES PATENT OFFICE.

MILAN HRNICH, OF CONEMAUGH, PENNSYLVANIA, ASSIGNOR OF ONE-HALF TO
RAFOELO GOYSSOVICH, OF CONEMAUGH, PENNSYLVANIA.

COMBINED CAR AND PIPE COUPLING.

1,226,887.

Specification of Letters Patent. Patented May 22, 1917.

Application filed October 9, 1916. Serial No. 124,591.

To all whom it may concern:

Be it known that I, MILAN HRNICH, a citizen of the United States, residing at Conemaugh, in the county of Cambria and

5 State of Pennsylvania, have invented certain new and useful Improvements in Combined Car and Pipe Couplings; and I do declare the following to be a full, clear, and exact description of the invention, such 10 as will enable others skilled in the art to which it appertains to make and use the same.

My invention has for its object to provide a simply constructed and inexpensive 15 coupler for train pipes equipped with improved means for yieldably holding the two coupling heads in engagement and for restoring said heads to their normal positions in case they be rotated in either direction.

20 With the foregoing general object in view, the invention resides in certain novel features of construction and in unique combinations of parts to be hereinafter fully described and claimed, the descriptive matter 25 being supplemented by the accompanying drawing which constitutes a part of this application, and in which:

Figure 1 is a side elevation of a pair of car couplers showing the application of the 30 improved train pipe coupler thereto, the parts being shown in the positions which they assume immediately before the cars are coupled;

Fig. 2 is a fragmentary view similar to 35 Fig. 1 showing the two heads of the improved coupler in operative position;

Fig. 3 is a horizontal section on substantially the plane of the line 3—3 of Fig. 2;

Fig. 4 is a perspective view showing the 40 two coupling heads; and

Fig. 5 is a similar view of one of the coupling heads used on freight trains.

In the drawings, the numerals 1 designate common types of coupling heads such as 45 those used on both freight and passenger cars, said heads, due to the nature of the present invention, having depending arms 2 whose lower ends are formed with circular openings 3 whose axes extend longitudinally of the cars upon which the heads 1 are mounted.

A pair of preferably circular coupling heads 4 are provided with cylindrical shanks or necks 5 mounted for sliding 55 movement as well as slight rotation in the

openings 3, said necks or shanks extending inwardly beyond the arms 2 and having caps 6 secured on their inner terminals by means of pins or the like 7.

Coiled springs 8 are interposed between the caps 6 and the arms 2, the ends of said springs being passed through openings 9 and 10 formed respectively through the arms 2 and caps 6, the terminals of said ends being bent laterally as indicated at 11 60 to anchor them. By locating the springs 8 and anchoring them in this manner they will exert their tension to normally force the two heads 4 outwardly away from the arm 2, thus causing said springs to be 65 placed under tension when said heads come in contact upon coupling of the heads 1, this tension serving to hold the coacting flat faces of said heads 4 in contact. The springs 8 anchored at their ends respectively to the caps 6 and the arms 2, will also hold the shanks 5 and heads 4 in normal position and will return them to such position even though they may rotate to a slight extent as the train equipped there- 70 with is passing over the road bed.

75 The heads 4 may be of any suitable construction, but the outer flat ends of said heads are preferably equipped with projecting semi-circular flanges 12, the flange of 80 each head serving to engage the unflanged edge of the other head as shown clearly in Fig. 3. Each head 4 is preferably formed with two ports 13 which open at their inner 85 ends through the flat faces of said heads, rubber gaskets 14 being here provided in order that fluid-tight connection may be 90 established between the ports of the two heads. The outer ends of the ports 13 pass through nipples 15 to which the usual train 95 pipes 16 are connected.

The type of head 4 so far described, that is the form employing two ports 13, is 100 designed primarily for use on passenger trains, but if the invention is to be employed on freight trains which use only a single pipe line, heads such as that shown at 4^a in Fig. 5 may be employed, this head having a single port 13^a increased in width at its outer end and here provided with a rubber gasket 14^a, the other end of the port being provided with a nipple 15^a by means of which the train pipe may be connected to the head. The head 4^a is provided with 105 a neck or shank 5^a identical with those 110

above described, and on one of its edges said head will preferably be equipped with a flange 12^a which is preferably straight rather than semi-circular as is the case with 5 the flange 12.

From the foregoing taken in connection with the accompanying drawings, it will be seen that although the construction of the improved hose coupler is comparatively 10 simple and inexpensive, the device will be highly efficient and durable. For these reasons, the exact construction shown and described constitutes the preferred form of the device, but it is to be understood that 15 within the scope of the invention as claimed, numerous changes may be made.

I claim:

The combination with a pair of car coupling heads; of rigid arms depending from 20 said heads and having circular guide openings formed therethrough, a pair of cou-

pling heads spaced outwardly from said arms in advance of the openings thereof, cylindrical shanks for said heads extending slidably and rotatably through the aforesaid openings to points spaced in rear of said arms, caps secured to the inner ends of said shanks and having bores parallel therewith, the lower ends of said arms also having bores parallel with said shanks, and 25 coiled springs surrounding said shanks between the arms and caps, said springs having straight ends anchored in the bores of said arms and caps.

In testimony whereof I have hereunto set 30 my hand in the presence of two subscribing witnesses.

MILAN HRNICH.

Witnesses:

W. P. REESE,
RAFAEL GOJSOVIC.
